CLAIM

The ornamental design for insulated beverage can holder, as shown and described.

DESCRIPTION

FIG. 1 is a perspective view of an insulated beverage can holder showing my new design;

FIG. 2 is a front elevational view thereof;

FIG. 3 is a rear elevational view thereof;

FIG. 4 is a side elevational view thereof;

FIG. 5 is a top plan view thereof; and,

FIG. 6 is a bottom plan view thereof.

The can shown in broken lines in FIG. 1 denotes the nature and environmental use of the design and is not part of the design.

FIG. 1

FIG. 2

FIG. 3

FIG. 5

FIG. 6

FIG. 4
